UNITED STATES PATENT OFFICE.

WILLIS W. RUSSELL, OF HIGHLAND PARK, NEW JERSEY, ASSIGNOR TO MARY N.
RUSSELL, OF MILLTOWN, NEW JERSEY.

PLAYING OR GAME CARD.

957,105.

Specification of Letters Patent.

Patented May 3, 1910.

Application filed March 19, 1909. Serial No. 484,474.

To all whom it may concern:

Be it known that I, WILLIS W. RUSSELL, a citizen of the United States, residing at Highland Park, in the county of Middlesex and State of New Jersey, have invented 5 new and useful Improvements in Playing or Game Cards, of which the following is a specification.

This invention relates to the standard 10 pack of playing cards bearing the conventional characters and containing the four suits, hearts, diamonds, clubs and spades and the denominations of each of these suits being the ace, king, queen, jack, ten, nine, 15 eight, seven, six, five, four, three and two besides the joker which makes the universally popular pack containing fifty-three cards; but while my invention is particularly intended to add an extra card to this 20 standard pack, the extra card is applicable to use in any pack of greater or less or any number of playing cards bearing the conventional characters such as pinochle and euchre decks and all decks of cards having less than 25 fifty-three cards as well as such decks of cards like the deck which contains in addition to the fifty-three cards of the standard pack the two denominations of eleven and twelve spots.

30 My invention and addition to any existing pack of conventional playing cards consists of an extra card, which I will designate as the "substitute" which bears the characters of the denominations and suits as shown in 35 Figure 1 but which may be arranged in any other manner desirable.

This invention is set forth in the following specification and claims and illustrated in the annexed drawing in which:—

40 Fig. 1 represents a pack of conventional playing cards with the "substitute" card lying on top making my improvement on the fifty-three card conventional pack one containing fifty-four cards. Fig. 2 shows 45 the face view of any card desired which is replaced by the extra card. Fig. 3 shows a manner of placing the "substitute" card into use.

Such "substitute" card comprises my improvement in the fifty-three card conventional pack making one containing fifty-four cards; but this extra card can be utilized 50 with different characters printed thereon

according to the denominations of the cards composing the pack.

In the case of any card which might have been damaged, marked or lost from the pack it would be impossible to utilize the pack of fifty-three cards without the convenience of having the "substitute" card.

55 The "substitute" card placed in use as a substitute for the card which has been damaged or lost from the pack, and the circle around a particular pip representing the denomination required is one way of utilizing the extra card, in order that the damaged pack can be used for all games for 60 which the fifty-three card conventional pack of cards is used. This circle described around the pip is not the only manner of 65 carrying out this invention but the designation can be reached by any kind of a mark desirable to the owner of the pack of cards.

The basic principle of my invention is the 70 making of a standard conventional pack of 75 cards to contain fifty-four cards instead of fifty-three as has been the custom.

75 My invention is intended to benefit the manufacturer, the merchant, the retailer and the consumer. It is a well known fact 80 that no matter how much care may be exercised by the manufacturer in inspecting his packs of playing cards for imperfections, very frequently packs of cards will reach the 85 merchant and from him to the consumer, that are defective and the principal trouble with which, most generally is the absence of one of the cards, caused through the carelessness of the inspection in the manufactory. My invention, therefore, saves a great deal 90 of expense, time and trouble for all concerned in the sale and use of a defective pack of cards by the "substitute" card which will correct the largest parts of these 95 difficulties.

This invention is applicable not only to the ordinary packs of cards but can be applied to cards or games of any variety, such for example as packs containing less than fifty-two or fifty-three cards, also double 100 packs like pinochle, skat, bezique, or any other kind or variety of pack of cards such as euchre, authors, logomachy, roulette and others.

I claim:—

105 1. A deck of playing or game cards in-

cluding a substitute card provided with denominating characters which correspond to all of the cards composing the deck whereby the substitute card may be appropriately marked on its face to take the place of any other card of the deck, the size shape and the appearance of the back of the substitute card corresponding precisely with the remaining cards of the deck.

10 2. As a new article of manufacture a substitute card adapted to replace any one of

the cards of a deck of playing cards and provided with indications of the suits and denominations of the various cards of the deck.

In testimony whereof I have hereunto set 15 my hand in the presence of two subscribing witnesses.

WILLIS W. RUSSELL.
